UNITED STATES PATENT OFFICE

JOHN M. HOTHERSALL, OF BROOKLYN, NEW YORK, ASSIGNOR TO AMERICAN CAN COMPANY, OF NEW YORK, N. Y., A CORPORATION OF NEW JERSEY

METHOD OF PRODUCING ONE-PIECE DRAWN CONTAINERS

Application filed February 13, 1929. Serial No. 339,560.

This invention relates to an improved method of producing a one-piece drawn sheet metal container provided with a flanged portion adapted for connection with a container cover.

In the manufacture of containers having drawn side walls, it has been customary to trim the edge after the drawing operation as a certain amount of edge irregularity results from the uneven strains introduced throughout the metal by the drawing action. Such containers prior to the present invention are first blanked, then formed (usually in the same machine) either directly from a sheet of material or from strips first sheared from the sheet. The latter practice is adapted to automatic production of such containers. In either method as a factor of safety the blanking line has been spaced at least an eighth of an inch from the sheet or strip edge to insure sufficient material remaining in the skeleton of the sheet or strip to permit of its being handled. This skeleton material constitutes a great waste. The blank must be sufficiently large to provide a drawn container and according to present methods to provide extra material as a factor of safety for a trim. This constitutes a second waste.

The present invention dispenses entirely with the blanking operation, the container being drawn directly from a scroll-shaped subdivision or section of the sheet without the usual remaining skeleton. There being no skeleton, the first waste mentioned is avoided. That part of the sheet, the section, from which the container is drawn according to the present invention does not follow the outline of the container as is usual where the container is first blanked and then drawn from the blank. Therefore, the usual allowance for a trim need not be made. That is to say, the trimming line, in the present invention, may coincide with the edge of the sheet part only at its narrowest place and the usual eighth of an inch allowance on both sides of the blank edge is thus saved.

The principal object of the present invention, therefore, is the provision of a process for the manufacture of a flanged, one-piece drawn container using a minimum number

of operations with a minimum waste of the material from which the container is made.

A further important object of the invention is the provision of a process for the manufacture of a flanged, one-piece, drawn container wherein the sheet from which the container is formed is first cut into a series of strips of a shape suitable for economic handling by automatic means and wherein divisions of the strip are used to form the container. 55

Numerous other objects and advantages of the invention will be apparent as it is better understood from the following description, which, taken in connection with the accompanying drawings, discloses a preferred embodiment thereof. 60

Referring to the drawings:

Figure 1 is a diagrammatic view of a sheet showing in full lines the outline of the scroll strips to be cut therefrom and indicating the extent of the sections of the strip by means of the dotted lines; 70

Fig. 2 is a perspective view of a drawn flanged shell body; 75

Fig. 3 is a perspective view of a completed drawn container;

Fig. 4 is a sectional fragmentary view of a conventional type of scroll strip cutting mechanism; 80

Fig. 5 is a transverse fragmentary view of a conventional drawing press mechanism;

Fig. 6 is a fragmentary plan view of part of the mechanism illustrated in Fig. 5;

Fig. 7 is a fragmentary, longitudinal sectional view, taken substantially along line 7-7 of Fig. 6, and;

Fig. 8 is a transverse, sectional fragmentary view of a conventional trimming mechanism. 85

A sheet 21 (Fig. 1) is first fed to a shearing mechanism which shears the same along lines of severance 22. For purposes of illustration, a drawn container of oval shape is selected and in the sheet lay-out for this shape of container, the lines of severance 22 are of scroll or undulating form, this giving scroll-shaped strips and a greater efficiency in cutting. The shearing operation divides the sheet into strips, there being disclosed a 95

central strip "A" and two outside strips "B". Different sheet lay-outs are used for different shapes and sizes of either container or sheet, Fig. 1 disclosing merely one preferred typical lay-out.

A strip "A" or "B" is then fed to cutting and drawing mechanism which first successively cuts off sections of the strip along the straight lines 23, thereby producing sections 10 "C". Following the cutting of each section "C" from the strip it is drawn into the form of the shell body "D" illustrated in Fig. 2. This produces a drawn shell 24 and an undrawn flange 25. This shell body "D" is then 15 fed to a trimming mechanism which removes the excess part of the flange 25, thereby forming the completed one-piece drawn container "E" provided with flange 26, as illustrated in Fig. 3.

20 It will be observed (Fig. 1) that the two strips "B" are narrower than the central strip "A", the upper line of severance 22 of upper strip "B" and the lower line of severance of lower strip "B" being incomplete. The entire 25 width of strip "A" is not required to form the container "E", the shell body (Fig. 2) when formed from a strip "B" having a part of the edge of its flange 25 cut away, as indicated by the dotted line 27. This, however, is inside 30 of or coincident at one point with the trimming line and the complete container "E" is always the same whether formed from a strip "A" or from a strip "B". This graphically 35 illustrates how, in the present invention, it is possible to dispense with the usual factor of safety as allowance for a trim. A relatively narrower sheet 21, which need not be trimmed, is thus used and a saving of the material results.

40 Notching dies in the shearing mechanism operate on sheet 21 (Fig. 1) to provide the resulting strips "A" and "B" with gauge reference notches. A gauged notch on each strip is used in connection with a complete 45 scroll side edge thereof to insure proper feeding of the strip through the cutting and drawing mechanism, as will be hereinafter fully set forth.

Strip "A" is accordingly provided with a 50 notch 28 while the strips "B" receive notches 29 and 31. Only one of the notches of strip "B" is used as a reference element, but two notches are cut by the notching dies in order to correctly position a notch relative to the 55 complete scroll edge thereof, regardless of whether it is the upper or the lower strip "B". This will become more apparent as the description proceeds.

The mechanism for cutting the strips from 60 the sheet 21 is illustrated in a general way in Fig. 4. This mechanism is of the usual type of metal shearing machine and comprises a supporting frame 32 which carries a bolster plate 33 formed as an integral part thereof.

65 An extension table 34 is also carried by the

frame 32 and forms the surface over which sheet 21 is moved through the machine. Bolster plate 33 carries a female shearing die 35, this constituting the stationary die element. A movable slide 36 carried in suitable guide-ways formed in the frame 32 supports a male shearing die 37 which constitutes the movable element of the shearing mechanism. The female die 35 is also formed with notching dies 38 and 39 which cooperate with corresponding die elements carried by the die 37. Die 35 also carries a notching die 41 which cooperates with a notching punch 42 carried by the slide 36.

70 As the sheet 21 is cut along the lines of severance 22, a strip "A" or "B" is pushed through the opening in the die member 35 and in a corresponding opening formed in the bolster plate 33 and falls onto a discharge chute 43. Part of the sheet which is positioned forward of the die 35 falls over an inclined surface 44 of the said die and certain rear parts of the sheet fall through an opening 45 and onto a discharge chute 46. The usual form of knock-out for the forward 80 strip or forward part of the sheet comprises a knock-out pin 47 slidably held in a bracket 48 projected from the forward face of the slide 36, and a spring 49 tends to hold the pin 47 in lowered position. Sheet 21 is fed 85 over the feed table 34 and through the die mechanism just described by feed bars 51 of usual construction sliding in guideways 52 formed in the table 34 and carrying spring-pressed dogs 53. A guide bar 54 is held 90 spaced above the surface of the table 34 and forms retaining means for sheet 21 as it is fed through the machine. Spring pressed or 95 gravity operated dogs 55 pivoted to bar 54 prevent backward travel of sheet 21 with the 100 return travel of feed bars 51.

105 In the lay-out disclosed in Fig. 1, sheet 21 is first positioned between the fixed and movable die mechanism so that the spaced scroll 110 cut edges of the die parts sever the upper strip "B" and move it downwardly through the lower die and onto the discharge chute 43. The irregular shaped pieces of the upper part of sheet 21 above the upper line of severance 22 during this cutting action fall over the inclined surface 44. During this cutting action, notches 29 and 31 are cut by the notching die parts 38 and 39 and the notch 28 is cut in the central strip "A" by the die parts 41 and 42.

115 The second position of sheet 21 severs the central strip "A" and the lower strip "B" from the sheet, the former being positioned forward of the die 35 and the latter being blanked and forced through the die onto the 120 discharge chute 43. At such time, the irregular shaped pieces on the lower edge of sheet 21 fall through opening 45 behind the dies and onto the chute 46.

125 The cutting and drawing mechanism com-

prises a standard form of press (illustrated in Figs. 5, 6, and 7). This mechanism comprises a supporting frame indicated at 56 having a supporting bed 57 formed integral therewith. A feed table 58 is mounted upon the bed 57 and forms the supporting surface over which the strips "A" or "B" are fed into the cutting and drawing mechanism. The cutting and drawing elements comprise 10 a drawing die 59 carried by the bed 57 and secured thereto by bolts 61. The drawing die 59 also carries cut edges 62 secured to opposite walls of the die. These constitute the stationary die elements.

15 The movable die elements comprise a slide 63 mounted in a usual or preferred manner and having up and down movement. The slide 63 carries a punch block 64 which is secured to the bottom end thereof by bolts 20 65. Cut edges 66 are screwed into the opposite sides of the punch block 64 and co-act with the cut edges 62 when the punch block is in lowered position. The drawing punch 67 is mounted within slide 63 and extends 25 through the punch block 64 and has movement relative to the slide and block. The drawing punch 67 cooperates with the drawing die 59 for forming the drawn shell body of the container in a manner hereinafter described. A knock-out pad 68 is positioned 30 within the opening formed in the drawing die 59 and is raised and lowered in proper time relation with the other operating parts of the press mechanism.

35 A knock-out rod 69 is secured to the pad 68 and forms the actuating connection therefor. Both slide and block and the drawing punch elements are actuated in proper time relation to effect the cutting of 40 strips "A" or "B" as they are fed over the table 58 by a standard form of feed mechanism.

As illustrated in Figs. 6 and 7, a strip "A" rests on the feed table 58 and is moved 45 toward the cutting and drawing mechanism just described by a feed bar 71 sliding in a guide-way formed in table 58 and carrying the usual standard type of pivoted spring-pressed feed dogs 72. The press mechanism 50 is inclined at an angle in the usual manner, as indicated in Fig. 5, and the strip "A" resting on table 58 is held by gravity against a rear guide 73 formed in table 58. In this 55 position of strip "A", the scroll edge adjacent slot 28 is against the guide 73. Where the upper strip "B" instead of strip "A" is used in the press, its full scroll edge is positioned against the guide 73, this bringing its notch 31 into proper feeding position. Where the lower strip "B" is in the press, its full scroll edge is positioned against the guide 73 and its notch 29 is in proper position. The feed bar 71 is moved back and forth to 60 move the strip through the machine, a feed 65

dog 72 engaging within a notch 28, 29 or 31 depending upon the kind of strip.

A locating device is used at the cutting and drawing station for properly centering the strip prior to the cutting of a section "C" 70 therefrom. This centering mechanism comprises centering blocks 74 and 75 mounted on rods 76 oscillating within suitable openings formed in the drawing die 59 and in bed 57. Fig. 6 illustrates in dotted lines the 75 position of the centering blocks as strip "A" or "B" is brought into cutting position. As the strip is brought to rest at the end of the forward stroke of feed bar 71, rods 76 are oscillated in any suitable manner to position 80 blocks 74 and 75, as illustrated by the full line position in Fig. 6. It will thus be readily seen that in this position the blocks 74 and 75 engage the scroll edges of the strip and center the end section "C" for cutting 85 and drawing. The slide 63 is thereupon lowered and cut edges 66 cooperate with their associated cut edges 62 and cutting along lines 23 of section "C" sever it from the remaining part of the strip. 90

In the event of a strip "A" being operated upon, the first cutting action severs an end piece "F" forward of the dies and removes the first section "C" from the end of the strip. This is illustrated in Fig. 6. In the 95 event that strip "B" is being operated upon, the first cutting action merely removes a small trim from the forward end of the strip.

Immediately following the cutting action, the punch block 64 continues its downward 100 movement and engages section "C" in a slip grip between the lower face of the block 64 and the upper surface of the drawing die 59. The drawing punch 67 then further descends and forces a part of section "C" into 105 the opening within the drawing die 59 to produce the drawn shell 24 of the shell body "D". Following the drawing action, punch 63 and associated parts are raised, the shell body "D" at such time remaining in the lower drawing die 59. Knock-out pad 68 is then 110 raised and the shell body "D" is lifted from position within the drawing die 59 to a position wherein its lower surface is in alignment with a discharge chute 77 formed between 115 the guides 78 formed on the feed table 58. To permit discharge of the shell body "D" from the die mechanism, the centering blocks 74 and 75 are moved to dotted position, as 120 illustrated in Fig. 6 whereupon the shell body "D" moves by gravity into the chute 77.

A chute 79 lies forward of and adjacent to chute 77 and has a side wall 78 in common with one wall of chute 77, and a wall 81 formed in the feed table 58. The end piece 125 "F" falls by gravity into chute 79 as soon as it is severed from the strip "A", and is thereby discharged out of the machine.

This cutting and drawing operation is repeated on strip "A" until at the final cutting 130

action, the rear end piece "G" is cut from the section "C" adjoining. The severed end piece "G" thereupon falls into a chute 82 in the rear of and adjacent to chute 77. Chute 82 has one side wall 78 in common with one of the walls of chute 77 and has a side wall 83 formed in the feed table. To permit discharge movement of end piece "G" by gravity within the chute 82, a gate 84 pivotally carried on the upper end of a rock shaft 85 oscillating in a bearing formed in table 58 is moved to the dotted position illustrated in Fig. 6. The gate 84 normally constitutes a continuation of the guide rail 73 when in the position illustrated in full lines in Fig. 6. In the event that a strip "B" is being operated upon, there is no end piece severed therefrom and the final cutting action removes the last section "C" without there being any remaining part of the strip.

The shell body "D" is then fed into a trimming mechanism, the principal parts of which are illustrated in Fig. 8. This may be any suitable form of trimming press comprising, for example, a supporting frame 86 and a supporting bed 87 formed integrally therewith. This is also inclined in the usual manner as illustrated in the drawing. A die block 88 is secured by bolts 89 to the bed 87 and constitutes the fixed part of the trimming mechanism. A slide 91, mounted in any suitable and usual manner for vertical movement, carries at its lower end a trimming punch 92 to which is secured a centering pad 93. The trimming punch 92 and centering pad 93 operate through an opening in a stripper ring 94 carried by bracket 95 mounted on the lower die 88.

The shell body "D" is positioned within the die 88 by a suitable and usual form of mechanism with its flange 25 resting on the upper surface of the die and the drawn shell part 24 resting within the opening of the die 88. Upon lowering of the slide 91, the centering pad 93 enters within the shell body 24 and the lower cut edge of the trimming punch 92 cooperates with the side walls adjacent the opening in the die 88 to cut from flange 25 a trimming skeleton "H".

The trimmed container "E" formed as a result of this action is pushed downwardly by continued lowering of the trimming punch 92 and falls by gravity through an opening 96 formed in the die 88 and through a similar opening 97 formed in the bed 87. The trimming skeleton "H" at such time encircles the trimming punch 92 and as the latter is raised, the skeleton is carried with it. As the trimming punch moves upward through the opening in the stripper ring 94, the trimming skeleton "H" striking against the under face of the stripper ring 94 is stripped off of the trimming punch 92 and falls by gravity onto the inclined plate 98 and slides out of the machine.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. The process of producing one-piece drawn containers which comprises shearing a sheet of material at intervals along lines of severance producing a series of scroll-shaped strips, cutting the strips at intervals along other lines of severance producing a series of sections, drawing each section along predetermined lines producing a body having a drawn shell and an undrawn flange, and trimming the flange along predetermined lines. 70
2. The process of producing one-piece drawn containers which comprises first presenting a sheet of material to a shearing operation which divides the sheet into scroll-shaped strips, second presenting a strip to a cutting operation which divides the strip into sections, third presenting the second to a drawing and forming operation which produces a flanged drawn body, and fourth presenting the body to a trimming operation which trims the flange and produces the completed one-piece drawn container. 90
3. The process of producing one-piece containers on automatically operating machinery which comprises presenting a sheet of material to a shearing mechanism and obtaining thereby scroll-shaped strips suitable for automatic feeding in an automatic strip press feed mechanism, feeding the strip automatically by such a feed mechanism to a cutting and forming press and obtaining therefrom a drawn, flanged shell body, and presenting said body to a trimming operation and obtaining therefrom the completed one-piece drawn container. 100
4. The process of producing non-rectangular, one-piece, drawn containers which comprises shearing a sheet of material along spaced, undulating lines of severance producing a series of scroll-shaped strips, cutting the strips along spaced straight lines of severance producing a series of sections, drawing a section into a shell part and an extended flange, and trimming the flange along a line parallel to the drawn wall of the shell part and producing the complete container. 110

JOHN M. HOTHERSALL. 125
